UNITED STATES PATENT OFFICE.

EMILIO CARDARELLI, OF BOSTON, MASSACHUSETTS.

COMBINATION LADDER.

Application filed July 12, 1927. Serial No. 205,200.

This invention pertains to combination stepladders of that type in which the rear or brace element of the ladder is adapted to slide relatively to the front or step member in order to produce an extension ladder, and relates more particularly to ladders of the kind disclosed in my copending application Serial No. 74,310, filed December 9, 1925, now Patent No. 1,635,705, granted July 12, 1927, of which this application is a part continuation. In my aforesaid application I have described the utility of my ladder (arranged as a step-ladder) for supporting a staging, as well as its adaptability for use on stairways or in like situations where the supporting element for the rear member of the ladder is higher than the support upon which the front member of the ladder rests.

I have now devised an improved ladder which, in addition to the utilities of my prior ladder, is capable of standing vertically upright even when extended and, if desired, supporting a staging while in this position. To this end, as well as to adapt the ladder to orchard use, I have provided certain adjunctive elements in combination with features of the ladder of my prior application (slightly modified and improved as to its details), and in the accompanying drawings I have illustrated my improved ladder together with those auxiliary devices which I provide for cooperation therewith.

In the accompanying drawings

Fig. 1 is a side elevation of my improved ladder structure arranged as a stepladder;

Fig. 2 is a rear elevation of the ladder shown in Fig. 1;

Fig. 3 is a fragmentary vertical section to larger scale on the line 3—3 of Fig. 2;

Fig. 4 is a fragmentary horizontal section on the line 4—4 of Fig. 3;

Fig. 5 is a fragmentary detail section on the line 5—5 of Fig. 2;

Fig. 6 is a vertical section showing the structure arranged as an extension ladder, leaning against a vertical surface;

Fig. 7 is a side elevation illustrating an arrangement employing two of my ladder devices extended and standing vertically upright to support a staging;

Fig. 8 is a fragmentary elevation to larger scale looking from the left-hand side of Fig. 7;

Fig. 9 is a rear elevation of an attachment useful in holding the extended ladder upright;

Fig. 10 is a fragmentary side elevation showing my ladder provided with an attachment enabling it to be used on a stairway;

Fig. 11 is a rear elevation of the attachment shown in Fig. 10; and

Fig. 12 is a fragmentary elevation, partly in section, showing an attachment designed to adapt the ladder for orchard use.

My improved ladder comprises the front (or step) portion 1 and the rear (brace or extension) member 2. The front member 1 comprises spaced side rails 3 and 4 preferably diverging from top to bottom and having flat guide bars 5 and 6 attached to their rear edges respectively. These guide bars preferably increase in width from top to bottom so as to provide a space of uniform width between their opposed edges and they extend downwardly to a point near but spaced from the lower ends of the rails 3 and 4 (Figs. 1 and 2).

The bars 5 and 6 are furnished with longitudinally extending guide grooves or rabbits 7 and 8 in their forward faces, the purpose of which is hereinafter described. The rails 3 and 4 carry a series of flat steps such as are commonly used in step-ladder constructions, the lowermost step being indicated at 9, the intermediate steps at 10, and the top step 11. A brace or abutment member 12 connects the rails 3 and 4 at a point just below the top step 11. Preferably this brace or abutment 12 is tenoned into the lower surface of the top step 11. In order to furnish a broad support for the front member of the ladder, particularly when it is to be used on soft ground, I provide broad feet 13 and 14 attached, removably, if desired, to the lower portions of the rails 3 and 4 and projecting laterally outward.

Near the upper end of the front member I provide a guide and retainer for the rear member 2. This guide or retainer 15 is preferably of U-shape, having its ends bolted to the uppermost of the intermediate steps 10 and its central portion 16 projecting rearwardly beyond the step.

The rear member 2 comprises the parallel side rails 17 and 18 which are held in spaced relation by means of the steps or rungs 19.

Near the lower end of the rear member 2 the rails 17 and 18 are also connected by means of an abutment brace 20. This brace preferably consists of a metal bar attached near its opposite ends to the rails 17 and 18 and preferably having a central brace lug 21 which is secured to the adjacent rung 19. The abutment brace 20 projects beyond the rails 17 and 18, thus providing the tongues 22 and 23 which are adapted to slide in the guide grooves 7 and 8 respectively of the guide members 5 and 6. The engagement of these tongues with the guide grooves prevents the rear member 2 from swinging outwardly and away from the front member 1. Preferably the lower ends of the rails 17 and 18 are provided with inwardly directed feet 13^a and 14^a respectively.

A swinging stop 24, of substantially U-shape, is pivotally secured at its opposite ends to the rails 17 and 18 of the rear member 2. This stop 24 hangs vertically, as shown in Fig. 1, when the structure is used as a step-ladder, but when employed as an extension ladder, as shown in Fig. 6, this stop 24 is swung forwardly and overlies one of the steps 9, 10, etc. of the front member. When in this position the stop member 24 also engages the lower edge of the metal abutment brace 20 which furnishes a rigid and unyielding surface through which the pressure of the extension member 2 is transmitted to the stop 24.

The rails 17 and 18 of the rear member 2 are provided with aligned openings near their upper ends, preferably above the uppermost rung 19, for the reception of a bar 25. The opposite ends 26 and 27 of this bar project beyond the rails 17 and 18 and are adapted to engage the parallel side members 16^b and 16^c of the guiding retainer 15. The forward edges of the rails 17 and 18 normally engage the rear edges of the steps of the front member 1 while the rear edges of the rails 17 and 18 are adapted to slide in contact with the member 16.

One end, for example the end 27, of the pivot bar 25 is preferably shaped to form a handle for withdrawing the bar when desired, but in order to prevent undesired longitudinal movement of the bar I provide a resilient retainer 28 consisting of a flat spring attached to the inner surface of one of the rails, for example the rail 18 of the rear member 2, such resilient member 28 normally pressing against the pivot bar 25 with sufficient force to prevent its accidental removal. The end 26 of the bar 25 is preferably screw threaded for the reception of a wing nut 35^a whose use is hereafter described.

When the ladder is employed as an extension ladder the parts assume positions such as shown in Fig. 6, the upper part of the extension or rear member being held in contact with the front member 1 by means of the retainer guide 16 while the lower parts of the ladders are held in proper relation by the

tongues 22 and 23 engaging the guide bars 5 and 6. The ladder is held in properly adjusted position by engagement of the stop 24 with a selected step of the front member. As thus arranged the upper end of the extension 70 may rest against a wall W or other surface and the combined structure is used like an ordinary extension ladder.

When the ladder is to be used as a stepladder the extension is dropped downwardly 75 until the tongues 22 and 23 escape beneath the lower ends of the guide bars 5 and 6. At this time the pin 25 rests upon the members 16^b and 16^c and the rear member 2 may be swung backwardly until its upper end strikes the 80 abutment member 12 shown in Fig. 3. In order to hold the ladder securely in this position I prefer to provide brace hooks 29 attached to the rear surfaces of the guide members 5 and 6 respectively and which may be 85 hooked into engagement with suitable eyes carried by the rails 17 and 18. When the ladder is not in use or when employed as an extension ladder the hooks 29 may be secured against swinging by engaging them with 90 suitable spring clips 29^a.

In order to adapt the ladder construction for use upon a stairway I provide a short rear member 2^a, as shown in Figs. 10 and 11, which may be substituted for the rear member 95 2 above described. This short rear member 2^a comprises the side rails 17^a and 18^a and the rungs 19^a. The rails 17^a and 18^a are furnished with openings 25^a at their upper ends for the reception of the pivot rod 25. This short rear 100 section may be substituted for the normal, or long rear section 2, merely by withdrawing the pivot rod, detaching the normal section by dropping it endwise from out the guide 16, and then thrusting the short section upwardly through the guide 16 and passing the pivot rod through the openings 25^a. This rear member 2^a may also be provided with eyes for engagement by the hooks 29. This short rear member is adapted, as shown in Fig. 10, to 110 rest upon a stair S while the lower end of the front member 1 rests upon the floor, thus permitting the steps 10 to remain in normal horizontal position and affording the desired stability for the ladder. When thus employed 115 the ladder may well form a support for one end of a plank or staging P.

Under some circumstances it may be desired to employ the ladder while extended for supporting a staging or plank, and in this case since the ladder can not always be inclined against a wall or other support and since the rear member when extended no longer constitutes a brace, it is necessary to provide some other means of holding the ladder upright. To this end I employ attachments such as shown in Figs. 7 and 9. The attachment shown in Fig. 9 preferably comprises a pair of brace legs 31 and 32 having openings 33 and 33^a at their upper ends re- 120 125 130

spectively for the reception of the rod 25 which at this time is not needed as a pivot. This rod is passed through vertically elongate openings 30 formed in the side rails 3 and 4 of the front section 1 of the ladder and the parts are held in assembled relation by tightening the wing nut 35^a. Preferably the brace legs 31 and 32 are connected by means of a folding strut comprising the members 36 and 37, each pivotally secured at one end to one of the legs or braces 31 and 32 and pivotally united at their other ends. I also prefer to furnish the legs 31 and 32 with pivoted braces 33 and 34 respectively adapted to be secured to the front section 1 by means of bolts passing through elongate slots in the rails 3 and 4. These braces 33 and 34, when not in use, may be secured against swinging by means of spring clips 35. When not in use this brace member, comprising legs 31 and 32, may be removed if desired and folded by collapsing the strut 36, 37, so that the combined structure occupies but small space, but when in use the members 31 and 32 are spread apart, the rod 25 is passed through the openings 33 and 33^a and through the slots 30, and the wing nut 35^a on the end of the rod is tightened to hold the parts securely in position. The legs 31 and 32 being swung outwardly, the braces 33 and 34 are fixedly secured to the rails 3 and 4 to hold the legs in proper position. The extended ladder 2^a (Fig. 7) may now stand upright without additional support and may be used for supporting one end of a plank or staging P.

In some situations I may prefer to employ a double brace structure instead of that shown in Fig. 9, and as indicated at the right-hand side of Fig. 7 this double brace structure may comprise two sets of the brace legs shown in Fig. 9, each set having hinge brackets 38 at its upper end, the hinge brackets of the two sets being provided with aligned openings for the reception of the rod 25 in the same way as above described in respect to Fig. 9. Each set of legs may be provided with pivoted braces 39 and 40 respectively, for holding them in properly extended position, and when thus extended the ladder structure 2^a is capable of standing upright without support from any other structure and the double brace furnishes a broad and substantial base so that the ladder may be extended to its uppermost limit without any tendency to tip. As thus arranged the ladder may also be used for supporting one end of a stage P.

By providing the elongate slots 30 for the pivot rod 25 and the elongate slots for the bolts holding the braces 34, 39 and 40 in position it is possible to adjust the braces to uneven ground and also to fold the legs with their lower ends flush with the ends of rails 3 and 4.

I have found that my ladder is particu-

larly useful for orchard work, for example in picking fruit or pruning trees, and in order to adapt it for this purpose I have provided, as shown in Fig. 12, a pointed nose member 41 which covers and protects the upper end of the ladder so that it may be thrust readily up among the branches of a tree and may find a proper support or rest in the crotch of a tree. This nose piece 41 preferably consists of sheet metal bent to shape and is provided with a pair of sockets 42 and 43 adapted to seat over the upper ends of the extension rails 17 and 18 respectively. These sockets are preferably provided with downwardly extending tongues 44 and 45 respectively having openings for the reception of the rod 25. The rod 25 thus has a three fold function, in removably holding the nosing 41 in position; in constituting a pivot for either of the interchangeable rear sections; and in forming clamping means for securing the auxiliary brace or braces to the front section.

I claim:

1. A ladder of the class described comprising a front section and a rear section, each section having spaced side rails and a plurality of steps, longitudinal guides secured to the rear edges of the rails of the front section, said guides having rabbets in their forward faces, lugs projecting from the lower part of the rear section into the rabbets of the respective guides, means retaining the upper part of the rear section in assembled relation with the front section, feet projecting outwardly from the lower ends of the front section, and feet projecting inwardly from the lower ends of the side rails of the rear section.

2. A ladder of the class described comprising a front section and a rear section, each section having spaced side rails and a plurality of steps, the rails of the front section being spaced more widely at the bottom than at the top and the rails of the rear section being substantially parallel, a flat guide secured to the rear edge of each rail of the front section, said guide increasing in width from the top of the section toward the bottom but terminating above the lower end of the front section, the front face of each guide being provided with a longitudinal rabbet, lugs projecting laterally from the lower part of the rear section into said rabbets, and means holding the upper part of the rear section in assembled relation with the front section.

3. A ladder of the class described comprising front and rear sections, each section having spaced steps, a U-shaped retainer guide projecting rearwardly from an upper step of the front section and embracing the rear section, a removable pivot pin normally passing through aligned openings in the side rails of the rear section, the ends of the pin being adapted to engage the U-shaped retainer guide, a resilient means for preventing acci-

dental longitudinal movement of the pin, and projections adjacent to the lower end of the rear section engageable with guide means on the front section for keeping the lower ends 5 of the front and rear sections in engagement as they are moved longitudinally relatively to each other.

4. A ladder of the class described comprising a front section and a rear section, each 10 section having spaced side rails and a plurality of steps, means for guiding the rear section to slide longitudinally of the front section, a pivot pin carried by the rear section and a retainer member on the front section 15 with which said pin may engage to form an axis about which the rear section may swing relatively to the front section, and a nose piece on the rear section having elements engageable with said pivot pin for holding it 20 in position.

5. A ladder of the class described comprising a front section and a rear section, each

section having spaced side rails and a plurality of steps, means for guiding the rear section to slide longitudinally of the front section, and a pointed nose piece having 25 socket members for the reception of the upper ends of the side rails of the rear section.

6. A ladder of the class described comprising a front section and a rear section, each 30 section having spaced side rails and a plurality of steps, means for guiding the rear section to slide longitudinally of the front section, a pointed nose piece for protecting the upper end of the rear section, said nose piece having sockets for the reception of the 35 ends of the side rails of the rear section, and a removable pin for holding the nose piece in position, said pin also constituting a pivot about which the rear section may swing relatively to the front section. 40

Signed by me at Boston, Massachusetts, this 27th day of June, 1927.

EMILIO CARDARELLI.
